UNITED STATES PATENT OFFICE.

HAROLD F. ELLIOTT, OF PALO ALTO, CALIFORNIA, ASSIGNOR TO AUGUSTUS TAYLOR,
OF SAN FRANCISCO, CALIFORNIA.

RADIOTELEGRAPHY SIGNALING SYSTEM.

Application filed August 23, 1921. Serial No. 494,468.

To all whom it may concern:

Be it known that I, HAROLD F. ELLIOTT, a citizen of the United States, and a resident of Palo Alto, Santa Clara County, State of California, have invented a certain new and useful Radiotelegraphy Signaling System, of which the following is a specification.

The invention relates to radio telegraphy signaling systems and particularly to a signaling system for use in connection with high power transmitting stations.

An object of the invention is to provide an efficient and effective signaling system for high power radio transmission stations.

Another object of the invention is to provide a uniwave signaling system for high power stations.

The invention possesses other advantageous features, some of which, with the foregoing, will be set forth at length in the following description, where I shall outline in full, those forms of the invention which I have selected for illustration in the drawings accompanying and forming part of the present specification. In said drawings I have shown several transmission systems embodying my invention, but it is to be understood that I do not limit myself to such forms, since the invention, as set forth in the claims, may be embodied in a plurality of other forms.

Referring to said drawings:

Fig. 1 is a diagrammatic representation of a uniwave signaling system embodying my invention and characterized by an untuned loop system.

Fig. 2 is a diagrammatic representation of a modified form of one signaling circuit.

Fig. 3 is a diagrammatic representation of a uniwave signaling system of my invention, comprising a tuned loop system.

Fig. 4 is a diagrammatic representation of a transmission system embodying my invention and employing an alternator as the source of radio frequency current.

Fig. 5 is a diagrammatic representation of a modified form of the system.

The system of my invention is particularly applicable to a continuous wave transmitting system and in the present embodiment I have shown it used in connection with a continuous wave arc generator 3 of the Poulsen type, but it is to be understood that it may be employed with other constant

frequency generators of radio frequency current. One side of the arc is grounded and the other side is connected to the antenna 4, through one winding of the transformer 5 and the inductance or main loading coil 6. When the system of this invention is used in connection with an arc radio generator in a uniwave signaling system, a non-radiating oscillatory circuit 7 containing the other winding of the transformer 5, an inductance coil 8, a capacity 9 and a variable resistor 12, is connected across the arc, but this non-radiating circuit may be omitted when an alternator or other constant frequency generator of radio frequency current is used.

In an arc system, means are provided for varying the impedances of the antenna circuit and the non-radiating circuit, so that the arc will be caused to oscillate on one circuit to the practical neglect of the other.

These means are usually operatively connected together, so that the impedances of the two circuits are varied simultaneously and oppositely. Inductively coupled to the inductor 6 by the loop 13 is a signaling circuit containing a plurality of voltage equalizing reactors 14 connected in series.

Connected around each reactor 14 is a key circuit containing a resistor 15 and key contacts 16. Inductively coupled to the inductor 8 by the loop 17 is a signaling circuit containing a plurality of voltage equalizing reactors 18 connected in series. Connected around each reactor 18 is a key circuit containing a resistor 19 and key contacts 21. The key contacts 16 and 21 are grouped at convenient points near the loading inductors 6 and 8 and are preferably operatively connected together, either mechanically or electrically, so that when the contacts 16 are opened, the contacts 21 are closed, and vice versa.

In Fig. 1 I have shown the contacts mechanically connected by a bar 22, but in practice solenoids will be employed for moving the contacts. The signaling circuits containing the loops 13 and 17 may be inductively associated with any suitable portions of the main circuits, or may be directly coupled to the main circuits by connecting the signaling circuits directly across or into portions of the main circuits. In theory, any method of connection may be used in which the operation of the keys serve to vary the constants of the main circuits,

90

105

but in practice, the inductive coupling is usually preferred.

When the key contacts are open, the current which flows in the associated loop circuit is limited by the reactors therein. The voltage across the key contacts depends upon the current through the reactors and may be made the same for all keys by installing the reactors so that they have negligible mutual coupling. When the key contacts are closed, the reactors are shunted by the resistors, whose impedance is low compared with that of the reactors themselves, and most of the current in the loop circuit flows through the resistors. This results in a change in the impedance of the main circuit with which the loop is coupled and signaling is accomplished by opening and closing the keys connected to the two circuits. This action, wherein one set of key contacts is opened and the other is closed, changes the values of the impedances of the two main circuits, that is the antenna circuit and the non-radiating circuits, simultaneously and oppositely, causing the radio frequency current to oscillate on one circuit to the practical neglect of the other.

Each loop circuit is grounded at points of equal potential, such as at the center of the loop, and at the center of the group of reactors, to carry off the charging currents and to limit the voltage above earth which exists at the key contacts. The proper installation of these ground connections and their arrangement so that additional voltage is not induced at the key contacts by the charging current are important features of this untuned loop system.

Instead of arranging the resistors in the key circuits and in shunt with relation to the reactors, resistors 23 may be connected directly in the loop circuits as shown in Fig. 2, although under certain conditions this may add appreciably to the resistances of the main circuits.

In Fig. 3 I have shown a modified form of the system used in connection with an arc in which the loop circuits are tuned to resonance at the frequency of operation when the keys are closed. In this system, the circuits of the keys and resistors are connected to the loop circuits through transformers 24. Each loop circuit is provided with means for tuning the circuit to resonance, and this means preferably comprises a capacitance 25 and an inductor 26, in each leg of the loop circuit. This tuning reduces to zero the reactance of the loop circuit and makes it possible to secure minimum residual current in the circuit on which the arc is not oscillating. When the keys associated with a loop circuit are closed, there is a large change in the impedance of the main oscillatory circuit to which the tuned loop is coupled with a re-

sultant reduction of the residual current therein to a small value.

By properly winding the transformers 24, the current-voltage duty on the key contacts may be adjusted to obtain the values which give best operation, and by properly insulating the windings of the transformers, one contact of each key may be grounded, which is desirable with certain types of keys.

Instead of using transformers, the keys may be connected directly around the reactors, as shown in Fig. 1, or they may be connected in any manner which will cause their opening and closing to alternately tune and detune the loop with which they are associated. The resistors may be connected directly in the loop, as shown in Fig. 2, and the loop circuit should be grounded as set forth in connection with the system disclosed in Fig. 1.

In Fig. 4 I have shown the system of my invention in a radio transmission system in which the source of radio frequency current is an alternator 27. When such a source is employed the use of a non-radiating circuit is not essential to the production of uniwave signals and, consequently, it is necessary to employ only one signaling circuit, the construction of which is the same as the signaling circuits heretofore described. In Fig. 4, the signaling circuit is inductively connected to the loading coil 6 of the antenna circuit, by the loop 13, but the signaling circuit may be directly connected to the loading coil or to other parts of the antenna circuit, as shown in Fig. 5, or may be directly connected into the antenna circuit.

Signaling circuits such as heretofore described may also be used for varying the impedance of only one main circuit when the source of radio frequency oscillations is either of constant or variable frequency and a non-radiating or second main circuit is or is not used.

While I have particularly described the application of the present invention to an uni-wave signaling system, it is understood that it may be employed in other signaling systems, wherein it is desirable to divide the load at a high power station among a plurality of key contacts. The loop system described herein may be advantageously employed wherever it is desirable to vary the constants of a circuit for signaling purposes.

I claim:

1. In a radio telegraphy signaling system, a source of radio frequency current, an oscillatory radiating circuit connected to said source, an oscillatory non-radiating circuit connected to said source, a loop circuit inductively coupled to one of said oscillatory circuits, a plurality of reactors in series in said loop circuit, and key circuits connected around said reactors.

2. In a radio telegraphy signaling system, a source of radio frequency current, an oscillatory radiating circuit connected to said source, an oscillatory non-radiating circuit connected to said source, a loop circuit inductively coupled to one of said oscillatory circuits, a plurality of reactors in series in said loop circuit, and means for varying the impedance of said loop circuit. 5
- 10 3. In a radio telegraphy signaling system, a source of radio frequency current, an oscillatory radiating circuit connected to said source, an oscillatory non-radiating circuit connected to said source, a loop circuit inductively coupled to one of said oscillatory circuits, a plurality of reactors in series in said loop circuit, and a circuit containing a key and a resistor connected around each reactor. 15
- 20 4. In a radio telegraphy signaling system, a source of radio frequency current, an oscillatory radiating circuit connected to said source, an oscillatory non-radiating circuit connected to said source, a loop circuit inductively coupled to one of said oscillatory circuits, a plurality of reactors in series in said loop circuit, key circuits connected around said reactors and means for simultaneously operating all of said keys. 25
- 30 5. In a radio telegraphy signaling system, a source of radio frequency current, an oscillatory radiating circuit connected to said source, an oscillatory non-radiating circuit connected to said source, a loop circuit inductively coupled to one of said oscillatory circuits, a plurality of reactors in series in said loop circuit, a circuit containing a key and a resistor connected around each reactor and means for simultaneously operating all 35
- 40 of said keys. 6. In a radio telegraphy signaling system, a source of radio frequency current, an oscillatory radiating circuit connected to said source, an oscillatory non-radiating circuit connected to said source, a loop circuit inductively coupled to one of said oscillatory circuits, a plurality of reactors in series in said loop circuit, means for varying the impedance of the loop circuit and means connecting the loop circuit to earth at points 45 of equal potential. 50
- 55 7. In a radio telegraphy signaling system, a source of radio frequency current, an oscillatory radiating circuit connected to said source, an oscillatory non-radiating circuit connected to said source, a loop circuit inductively coupled to each oscillatory circuit, a plurality of reactors in series in each loop circuit and means for oppositely varying the 60
- 65 impedances of said loop circuits. 8. In a radio telegraphy signaling system, a source of radio frequency current, an oscillatory radiating circuit connected to said source, an oscillatory non-radiating circuit connected to said source, a loop circuit in-
- ductively coupled to each oscillatory circuit, a plurality of reactors in series in each loop circuit, and means for simultaneously and oppositely varying the impedances of said loop circuits. 70
9. In a radio telegraphy signaling system, a source of radio frequency current, an oscillatory radiating circuit connected to said source, an oscillatory non-radiating circuit connected to said source, a loop circuit inductively coupled to each oscillatory circuit, a plurality of reactors in series in each loop circuit and key circuits connected around said reactors. 75
10. In a radio telegraphy signaling system, a source of radio frequency current, an oscillatory radiating circuit connected to said source, an oscillatory non-radiating circuit connected to said source, a loop circuit inductively coupled to each oscillatory circuit, a plurality of reactors in series in each loop circuit and a circuit containing a key and a resistor connected around each reactor. 80
11. In a radio telegraphy signaling system, a source of radio frequency current, an oscillatory radiating circuit connected to said source, an oscillatory non-radiating circuit connected to said source, a loop circuit inductively coupled to each oscillatory circuit, a plurality of reactors in series in each loop circuit, a circuit containing a key and a resistor connected around each reactor and means for simultaneously operating all 85
- 90 of said keys. 12. In a radio telegraphy signaling system, a source of radio frequency current, an oscillatory radiating circuit connected to said source, an oscillatory non-radiating circuit connected to said source, a loop circuit inductively coupled to each oscillatory circuit, a plurality of reactors in series in each loop circuit, means for oppositely varying the impedances of the loop circuits and means connecting each loop circuit to earth 95
- 100 at points of equal potential. 13. In a radio telegraphy signaling system, a source of radio frequency current, an oscillatory radiating circuit connected to said source, an oscillatory non-radiating circuit connected to said source, a loop circuit tuned to resonance at the frequency of operation inductively connected to one of said circuits and signaling means for varying the impedance of the loop circuit. 110
- 115 14. In a radio telegraphy signaling system, a source of radio frequency current, an oscillatory radiating circuit connected to said source, an oscillatory non-radiating circuit connected to said source, a loop circuit tuned to resonance at the frequency of operation inductively connected to one of said circuits and signaling means for detuning said loop circuit. 120
15. In a radio telegraphy signaling sys-

- tem, a source of radio frequency current, an oscillatory radiating circuit connected to said source, an oscillatory non-radiating circuit connected to said source, a loop circuit 5 tuned to resonance at the frequency of operation inductively connected to one of said circuits, a plurality of reactors in series in said loop circuit and key circuits connected around said reactors.
10. 16. In a radio telegraphy signaling system, a source of radio frequency current, an oscillatory radiating circuit connected to said source, an oscillatory non-radiating circuit connected to said source, a loop circuit 15 tuned to resonance at the frequency of operation inductively connected to one of said circuits, a plurality of reactors in series in said loop circuit, key circuits connected around said reactors and means for simultaneously operating all of said keys.
15. 17. In a radio telegraphy signaling system, a source of radio frequency current, an oscillatory radiating circuit connected to said source, an oscillatory non-radiating circuit 20 connected to said source, a loop circuit tuned to resonance at the frequency of operation inductively connected to one of said circuits, reactors in series in the loop circuit, a circuit containing a key and a resistor 25 connected around each reactor and means for simultaneously operating all of said keys.
20. 18. In a radio telegraphy signaling system, a source of radio frequency current, an oscillatory radiating circuit connected to 30 said source, an oscillatory non-radiating circuit connected to said source, a loop circuit tuned to resonance at the frequency of operation inductively connected to one of said circuits, means for varying the impedance 35 of the loop circuit and means connecting the loop circuit to earth at points of equal potential.
25. 19. In a radio telegraphy signaling system, a source of radio frequency current, an oscillatory radiating circuit connected to 40 said source, an oscillatory non-radiating circuit connected to said source, a loop circuit tuned to resonance at the frequency of operation inductively connected to one of said 45 circuits, a plurality of reactors in series in said loop circuit, and a key associated with each reactor, said loop circuit being in resonance when the keys are closed.
30. 20. In a radio telegraphy signaling system, a source of radio frequency current, an oscillatory radiating circuit connected to 50 said source, an oscillatory non-radiating circuit connected to said source, a loop circuit tuned to resonance at the frequency of operation inductively connected to each of said 55 circuits, and means for oppositely varying the impedances of said loop circuits.
35. 21. In a radio telegraphy signaling system, a source of radio frequency current, an oscillatory radiating circuit connected to 60 said source, an oscillatory non-radiating circuit connected to said source, a loop circuit tuned to resonance at the frequency of operation inductively connected to each of said 65 circuits, and means for oppositely varying the impedances of said loop circuits and means connecting each loop circuit to earth at 70 points of equal potential.
75. said source, an oscillatory non-radiating circuit connected to said source, a loop circuit tuned to resonance at the frequency of operation inductively connected to each of said 75 circuits, and means for simultaneously and oppositely varying the impedances of said loop circuits.
80. 22. In a radio telegraphy signaling system, a source of radio frequency current, an oscillatory radiating circuit connected to 80 said source, an oscillatory non-radiating circuit connected to said source, a loop circuit tuned to resonance at the frequency of operation inductively connected to each of said 85 circuits, a plurality of reactors in series in each loop circuit and key circuits connected around said reactors.
85. 23. In a radio telegraphy signaling system, a source of radio frequency current, an oscillatory radiating circuit connected to 90 said source, an oscillatory non-radiating circuit connected to said source, a loop circuit tuned to resonance at the frequency of operation inductively connected to each of said 95 circuits, a plurality of reactors in series in each loop circuit and a circuit containing a key and a resistor connected around each reactor.
95. 24. In a radio telegraphy signaling system, a source of radio frequency current, an oscillatory radiating circuit connected to 100 said source, an oscillatory non-radiating circuit connected to said source, a loop circuit tuned to resonance at the frequency of operation inductively connected to each of said 105 circuits, a plurality of reactors in series in each loop circuit, a circuit containing a key and a resistor connected around each reactor and means for simultaneously operating all 110 of said keys.
110. 25. In a radio telegraphy signaling system, a source of radio frequency current, an oscillatory radiating circuit connected to 115 said source, an oscillatory non-radiating circuit connected to said source, a loop circuit tuned to resonance at the frequency of operation inductively connected to each of said 120 circuits, a plurality of reactors in series in each loop circuit, a circuit containing a key and a resistor connected around each reactor, and means for simultaneously opening the keys associated with one circuit and closing the keys associated with the other circuit.
125. 26. In a radio telegraphy signaling system, a source of radio frequency current, an oscillatory radiating circuit connected to 125 said source, an oscillatory non-radiating circuit connected to said source, a loop circuit tuned to resonance at the frequency of operation inductively connected to each of said 130 circuits, means for oppositely varying the impedances of said loop circuits and means connecting each loop circuit to earth at 130 points of equal potential.

27. In a radio telegraphy signaling system, a source of radio frequency current, an oscillatory radiating circuit connected to said source, an oscillatory non-radiating circuit connected to said source, a loop circuit tuned to resonance at the frequency of operation inductively connected to each of said circuits, a plurality of reactors in series in each loop circuit, and a key associated with each reactor, each loop circuit being in resonance when the keys associated therewith are closed.
28. In a radio telegraphy signaling system, a source of radio frequency current, an oscillatory radiating circuit connected to said source, a loop circuit inductively coupled to said circuit, a plurality of reactors in series in said loop circuit and key circuits connected around said reactors.
29. In a radio telegraphy signaling system, a source of radio frequency current, an oscillatory radiating circuit connected to said source, a circuit connected to said radiating circuit, a plurality of reactors in series in said connected circuit and key circuits connected around said reactors.
30. In a radio transmitting system, a source of radio frequency current, a radiating circuit connected to said source, and means for varying the constants of the radiating circuit, comprising a plurality of independent reactors, means for so connecting these reactors to the radiating circuit that radio frequency current from the source may flow through them in series, and means for varying the impedances of the reactors.
31. In a radio telegraphy signaling system, a source of radio frequency current, an oscillatory radiating circuit connected to said source, a circuit connected to said radiating circuit, a plurality of reactors in series in said connected circuit, and a circuit containing a key and a resistor connected around each reactor.
32. In a radio telegraphy signaling system, a source of radio frequency current, an oscillatory radiating circuit connected to said source, a circuit connected to said radiating circuit, a plurality of reactors in series in said connected circuit, key circuits connected around said reactors, and means for simultaneously operating all of said keys.
33. In a radio telegraphy signaling system, a source of radio frequency current, an oscillatory radiating circuit connected to said source, a circuit connected to said radiating circuit, a plurality of reactors in series in said connected circuit, a circuit containing a key and a resistor connected around each reactor, and means for simultaneously operating all of said keys.
34. In a radio telegraphy signaling system, a source of radio frequency current, an oscillatory radiating circuit connected to said source, a plurality of reactors in series in said connected circuit, a circuit tuned to resonance at the frequency of operation inductively connected to said radiating circuit, a plurality of reactors in series in said loop circuit and a circuit containing a key and a resistor connected to each reactor.
35. In a radio transmitting system, a source of radio frequency current, a radiating circuit connected to said source, and means for varying the constants of the radiating circuit, comprising a circuit tuned to the frequency of operation, means for connecting said circuit so as to parallel a portion of the radiating circuit impedance, and a variable reactor in series with the tuned circuit.
36. In a radio telegraphy signaling system, a source of radio frequency current, an oscillatory radiating circuit connected to said source, a circuit tuned to resonance at the frequency of operation connected to said radiating circuit, a plurality of reactors in series in said connected circuit and key circuits connected around said reactors.
37. In a radio telegraphy signaling system, a source of radio frequency current, an oscillatory radiating circuit connected to said source, a circuit tuned to resonance at the frequency of operation connected to said radiating circuit, a plurality of reactors in series in said connected circuit and a circuit containing a key and a resistor connected to each reactor.
38. In a radio transmitting system a source of radio frequency current, a radiating circuit connected to said source, and means for varying the constants of the radiating circuit, comprising a circuit tuned to the frequency of operation and inductively coupled to a portion of the radiating circuit impedance, and a variable reactor in series with the tuned circuit.
39. In a radio telegraphy signaling system, a source of radio frequency current, an oscillatory radiating circuit connected to said source, a loop circuit tuned to resonance at the frequency of operation inductively connected to said radiating circuit, a plurality of reactors in series in said loop circuit and keys connected around said reactors.
40. In a radio telegraphy signaling system, a source of radio frequency current, an oscillatory radiating circuit connected to said source, a loop circuit tuned to resonance at the frequency of operation inductively connected to said radiating circuit, a plurality of reactors in series in said loop circuit and a circuit containing a key and a resistor connected to each reactor.

In testimony whereof, I have hereunto set my hand.

HAROLD F. ELLIOTT.
